GEORGE H. LOCUSON, OF PHILADELPHIA, PENNSYLVANIA.

FLYING-MACHINE.

1,387,501.

Specification of Letters Patent. Patented Aug. 16, 1921.

Application filed August 30, 1917. Serial No. 188,894.

To all whom it may concern:

Be it known that I, GEORGE H. LOCUSON, a citizen of the United States, and a resident of the city of Philadelphia, county of Philadelphia, and State of Pennsylvania, have invented certain new and useful Improvements in Flying-Machines, of which the following is a specification, reference being had to the accompanying drawings.

10 My invention relates to flying machines of the heavier-than-air type, and among the principal objects of the invention are to provide a flying machine adapted for vertical ascension from the ground and comprising 15 means effective both to elevate the flying machine in a vertical direction as aforesaid, and, when desired, to propel the machine forwardly, or to check its forward motion, meanwhile maintaining the machine at the 20 desired height above the earth.

Further objects of my invention are to provide a flying machine comprising a plurality of wings or planes arranged for revolution in planes normal to the longitudinal 25 axis of the frame of the machine and in opposite directions with respect thereto, and embodying means whereby the path of revolution of the respective wings or sets of wings may be varied as desired to thereby 30 control the power effectively exerted by the wings to lift the machine vertically.

Further objects of my invention are to provide a flying machine having wings and wing controlling means of the aforesaid nature, in 35 which the wings are so arranged that complete inversion of each wing about its individual axis of movement during the revolution of the wing-carrying arms is not effected, thus permitting the employment of 40 a wing of concave transverse section whereby the efficiency of the wing, both as a lifting and as a driving medium, is increased over that attained by the employment of a flat wing.

45 A still further object of my invention is to provide in a flying machine having a plurality of revolute wings, means for simultaneously effecting inclination of the individual wings while in motion to thereby 50 render said wings effective to propel the flying machine forwardly or to check its forward movement as desired.

Still further objects of my invention are to provide in a flying machine a novel form 55 of rudder effective to guide the machine both in horizontal and vertical directions, which

is of simple construction and easily controlled by the operator of the machine.

My invention further includes all of the other various novel objects and features of 60 construction and arrangement hereinafter more definitely specified and described.

I shall now proceed to describe one embodiment of my invention, which is illustrated in certain instances more or less diagrammatically, in the accompanying drawings, but I do not desire or intend to thereby limit myself specifically to such embodiment, as I may employ any suitable means and instrumentalities other than those shown 70 in the drawings and hereinafter described, which are suitable for effecting the objects of my invention.

In the accompanying drawings, Figure 1 is a top plan view of a flying machine constructed in accordance with one form of my invention; Fig. 2, a transverse vertical section thereof taken on line 2—2 in Fig. 1, certain of the controlling mechanism being omitted for the sake of clearness; Fig. 3, an 80 enlarged fragmentary view of one of the wing units looking toward the front of the machine; Fig. 4, a fragmentary top plan view of one of the wings shown in Fig. 3; Fig. 5, a fragmentary view showing 85 an end elevation thereof; Fig. 6, a similar view illustrating various positions which may be assumed by a wing when the machine is in operation under certain conditions; Fig. 7, a fragmentary view 90 looking in the direction of the line 7—7 in Fig. 3; Fig. 8, a fragmentary plan view partially in central section showing a portion of the wing adjusting operating mechanism in detail; Fig. 9, a view substantially similar 95 to Fig. 2 but taken on line 9—9 in Fig. 1, illustrating the action of the wings in a different operative position; Fig. 10, a fragmentary detail view in side elevation showing the rudder and a portion of its controlling mechanism; and Fig. 11, a fragmentary 100 cross-sectional view on line 11—11 in Fig. 1.

Referring now to the drawings, the form of the invention shown therein comprises a preferably substantially triangular longitudinally extending frame having cross members 1, side members 2, 2' suitably braced and connected together, from which, one each side, outwardly and upwardly extending and converging members 3, 3' and 110 4, 4' project, which serve adjacent their points of intersection to support suitable

bearings carrying the wing driving shafts 6, 6' which extend longitudinally on each side of the frame and serve to effect the rotation of the wings as hereinafter described. 5 The frame may be supported on suitable wheels 8 so that it may be easily moved about when resting on the ground, and for furnishing the power to operate the machine a suitable motor or engine 10 is mounted on the frame, preferably substantially midway from its ends, and suitably connected with shafts 6, 6' preferably by driving chains 11, 11' passing over suitable sprockets 12, 12' in turn driven through gearing 13, in such 15 manner that the shafts 6, 6' may rotate outwardly and in opposite directions, a suitable clutch 15 interposed between the motor and gearing 13 being effective through suitable controlling means, actuated for example by 20 a lever 16 near the operator's seat 17, to disconnect the motor from the gearing when desired.

It will be understood that the power generated by the motor is utilized to actuate a 25 plurality wing units each consisting preferably of three separate wings, the units being respectively oppositely disposed in pairs transversely of the frame, means being provided to alter the path of rotation of the 30 wings in each individual unit to thereby modify the lifting force exerted by the wings, as well as means to vary the angle of inclination of each individual wing in each 35 unit to thereby render the wings effective to drive the machine ahead while simultaneously maintaining it in the air, or to retard the forward progress of the machine in the air, as desired.

It will be further understood that each of 40 the wing units is substantially similar in construction and operation to all of the other units, and that any desired number of pairs of units may be utilized in the construction of the machine, the form of machine shown 45 comprising two pairs located adjacent opposite ends of the frame and respectively in front of and behind the motor. I shall now proceed to describe the construction and operation of one of the wing units, which description will, of course, apply equally well 50 to all of the other units, the corresponding parts of which are designated by similar numbers in the drawings with the exception that those numbers referring to elements on 55 the left hand side of the machine, looking toward its front end, are differentiated from the numbers for corresponding elements on the right hand side of the machine by the addition of a prime (').

60 Each unit comprises three pairs of arms 20 and 21 extending radially outward from the driving shaft 6 and operatively rigidly fixed thereto, the arms being equi-distantly spaced about the shaft and the outer end of 65 arm 21 being forked, so that it forms a Y

when viewed as in Fig. 3. Positioned between each pair of arms and rigidly attached to a shaft 25 is a wing 27 formed of any suitable material and which may preferably be substantially elliptical in planular outline, the wing being preferably concave on its under, and convex upon its upper side and thereby effective to exert a maximum lifting power as hereinafter described. The forward end of the shaft 25 is carried in a 70 suitable bushing 26 rigidly positioned on the adjacent arm 20, a universal joint 28 being interposed in the shaft between the wing and the bushing. A crank 30 is mounted on the shaft and connected by a link 31 with one arm of another crank 32, the other arm of which extends through a suitable bearing in the arm 20 and carries adjacent its forward extremity a gear 35, which meshes with a second gear 36 rotatably 80 mounted on a stud projecting from arm 20, which gear, in turn, meshes with a third gear 37 which has the same number of teeth as the gear 35 and is carried by a sleeve 38 surrounding, but relatively movable with respect to, the drive shaft 6, the sleeve being provided with a radial extending crank 40. This crank, in turn, is connected by link 41 with another crank 42 mounted on a shaft 43 extending longitudinally of the machine 95 and arranged for manual rotation by the operator of the machine in any suitable manner, as, for example, and as shown in the drawings, by a chain 44 passing over a sprocket 45 on the shaft and another sprocket 100 46 on a small stub shaft extending longitudinally of the machine and controlled by a hand wheel 47 adjacent the operator's seat, substantially similar controlling means being arranged to actuate the shaft 43', so that 105 by rotation of the hand wheel the operator may simultaneously actuate shafts 43 and 43' but in opposite directions, and thereby swing cranks 40 and 40' inwardly or outwardly to correspondingly turn gears 37, 37' 110 for a purpose to be hereinafter described.

The rear end of each shaft 25 is provided with a double fork said fork being free to rotate relative to said shaft 25 and adapted to engage a curved guide bar 50 supported between the ends of the forked portion of arm 21, the radius of curvature of the bar being substantially equal to the distance between the bar and the center of the universal joint 28. 115

Suitable means are provided for positioning each shaft 25 in any desired position with respect to its guide-bar to correspondingly effect the raising or lowering of the rear edge of the wing and to maintain the shaft in such desired position, which may vary from one in which the shaft is intermediate of the ends of the guide-bar to one in which it is adjacent either end thereof as best shown in Figs. 5 and 6. Such means 125 130

may preferably consist of a screw 53 supported from and paralleling the guide-bar and secured, through the medium of a universal joint 54 to a stub shaft 55 extending 5 through a lug 56 integral with one of the forked portions of arm 21 and carrying a bevel gear 58 meshing with another gear 59 on a shaft 60 extending substantially parallel with said forked portion of the arm 10 and supported by lugs integral therewith. The end of shaft 60 opposite to that carrying bevel gear 59 is connected, through the medium of a universal joint 62, with another shaft 63 extending parallel to and supported 15 upon the main portion of arm 21 and carrying at its opposite end a bevel pinion 65 as best shown in Figs. 4 and 8. Screw 53 is provided with a nut 70, carrying a forked arm 71 which engages the guide-bar 50 between the forks on the end of shaft 25 in such manner that the rotation of screw 53 and consequent movement of the nut thereon, will cause the arm 71 to carry the forked end of shaft 25 along the guide-bar and 25 thereby move the shaft from a position equidistant from the ends of the guide-bar as shown in Fig. 5, to a position adjacent either end thereof, as shown in Fig. 6, or to any intermediate position.

30 Suitable means are provided for effecting, when desired, the simultaneous rotation of all of the pinions 65, 65' in either direction as well as for holding the pinions stationary, such means, best shown in Fig. 8, preferably 35 consisting of a pair of bevel gears 80 and 81 surrounding the wing driving shafts adjacent each wing unit and in constant engagement with the three adjacent pinions 65 or 65' as the case may be, which bodily revolve with frame 21, in combination with means whereby both gears 80 and 81 may be permitted to revolve loosely, or be alternately held in fixed position. While any suitable means may be provided for accomplishing this result, the gears may preferably 40 be mounted on a sleeve 83 surrounding the wing driving shaft and reduce in diameter adjacent its center to provide shoulders 84 against which the gears abut and are thereby maintained in constant engagement with the pinions. One end of the sleeve abuts against the arms 21 and the other extends through, and is fixedly secured to, the frame member 3, as by a set screw 45 50 and for convenience in assembling, the sleeve may be made in two parts, as shown, connected together by a collar 86 removably attached, as by screws 87, to both members of the sleeve, thereby operatively uniting them. Suitable clutches are provided 55 for alternately engaging the gears to hold them in fixed relation with the sleeve, consisting, conveniently, of cones 90 and 91 arranged respectively to engage in recesses 60 in the outer faces of the gears and actuated by a member 92 extending through a suitable groove or grooves 93 in the sleeve, one end of which projects beyond the outer extremity of the sleeve and carries an integral lug 95. The cones are operatively secured 70 to member 92 as by screws 96, in such manner that the cones are separated for a distance greater than the distance between the portions of the gears which they are respectively adapted to engage, so that with 75 member 92 in intermediate position neither cone will engage its gear, while longitudinal movement of the member will force either of the cones into engagement with its adjacent gear to hold the same in fixed relation with 80 the sleeve, movement of the member in the opposite direction being effective to similarly position the other gear and to disengage the first-mentioned gear to permit its rotation with respect to the shaft. It will thus be 85 evident that if either gear be held stationary by the operation of its respective clutch during rotation of arms 20 and 21, the pinions 65 will be simultaneously caused to rotate, thereby actuating screws 53 in the adjacent 90 wing unit to raise or lower the rear edges of the wings, depending upon the direction of rotation of pinion 65, and that if both cones are disengaged from their respective gears, the latter are free to be carried around on 95 sleeve 83 with pinions 65 without causing any axial rotation of the latter and consequent motion of screws 53, the nuts 70 being maintained on the screws in the positions in which they were at the instant the cones 100 were disengaged.

In order to effect the simultaneous angular adjustment of all of the wings of the machine when desired by the operator, each of the members 92 is pivotally connected 105 with a lever 100, conveniently fulcrumed to the adjacent frame member 3 and extending downwardly and inwardly toward the body of the machine, the lower ends of the levers from each pair of oppositely disposed wing 110 units being connected by a transversely extending cross bar 101, all of which bars are in turn connected together by a longitudinally extending draw bar 102 controlled by a hand lever 103 adjacent the operator's seat 115 so that by suitable actuation of this lever all of the clutches may be simultaneously operated to permit the rotation of the various pinions 65 or to prevent their rotation and in turn effect the angular adjustment of 120 the wings or maintain any given adjustment thereof as may be desired. If desired, however, any other suitable method of operating the various clutches either separately or simultaneously may be employed.

125 For controlling the direction of flight of the machine, both horizontally and also to a certain extent vertically, the machine is provided, preferably adjacent its front end, with a rudder 125 preferably consisting of 130

a pair of rectangular planes disposed normally to each other and in angular relation to the horizontal, each plane, when viewed as in Fig. 11, forming approximately an angle of 45° therewith. The rudder may be supported between a pair of forwardly and upwardly extending arms 128 rigidly secured to a cross member 129 adjacent the forward end of the machine, and is preferably suspended at its forward end by a horizontally disposed yoke 130 secured to the rudder and having a pair of eyes engaging a curved horizontally positioned guide-bar 131 rigidly secured to the outer extremities of members 128, and at its rear end by a substantially similar yoke 133 positioned at right angles to the first-mentioned yoke and engaging an inwardly curved guide-bar 134 extending vertically from the upper part of the main frame to the cross member 129.

For the purpose of effecting the movement of the rudder in a horizontal plane, a cable 136 is led from one side of yoke 130 rearwardly over suitable pulleys or sheaves and about a drum 138, controlled by a hand wheel 140 adjacent the operator's seat, and thence around other sheaves at the opposite side of the machine and forwardly to the other side of yoke 130, so that revolution of the hand wheel will serve to move the forward end of the rudder transversely in either direction when desired, to correspondingly direct the course of the machine. In a substantially similar manner a cable 135 may be arranged to control the vertical position of the rear end of the rudder, as best shown in Fig. 10 the cable 145 passing upwardly from yoke 133, over suitably positioned sheaves and thence to and about a conveniently positioned drum 147 controlled by a hand wheel 148, from which the cable is led back over other suitably positioned sheaves to the under side of yoke 133, so that revolution of the hand wheel 138 will result in corresponding movement of the rear end of the rudder, and consequent change in the course of the machine in a vertical plane, the arrangement being such that the operator may by manipulation of the hand wheels readily control both the course of the machine from right to left and vice versa, as well as direct it upwardly or downwardly, as may be desired. Of course, other suitable means than those illustrated may be employed for controlling the rudder if desired, or the said means may be suitably modified in minor particulars.

With the parts constructed and assembled preferably substantially as hereinbefore described, the operation of the machine may be briefly described as follows. Presuming the machine to be resting upon the ground upon its supporting wheels 8, the machine may be caused to rise vertically by starting the motor and by manipulation of

clutch 15, causing the wing drive shafts 6, 6' to rotate to cause the revolution of the wings in opposite directions. It will be understood that in order to derive the maximum lifting power from the wings, the cranks 40 will be set in such a position that gears 37 will assume substantially the position shown in Fig. 2 in which the wings are operative to exert the greatest downward pressure, being horizontal at the center of their downward sweep and quickly turned from that position to move substantially vertically upward, thereby cutting through, as distinguished from pressing facewardly on the air, on the upward sweep, known in the art as "feathering." After the machine has risen substantially vertically to the desired height, suitable manipulation of cranks 40, and consequent rotation of gears 37, will be effective to change the position of the several cranks 32 with respect to the arms 20, and in turn modify the relative position of any given wing at any given point in its cycle of revolution, and thus change the "feathering" action which takes place, so that, for example, instead of the wings consecutively assuming the various positions shown principally in dotted lines in Fig. 2, (in which consecutive positions of the wings and adjacent cranks and links are diagrammatically indicated) and in which they are effective to exert a maximum lifting power, they may be caused to consecutively assume the positions similarly shown in Fig. 9, in which positions the lifting power of the wings, as clearly shown, is materially modified, each wing in its downward sweep being less effective to exert a maximum lifting power and in its upward sweep, exerting a greater resistance upon the air. In consequence, if the wings, positioned as shown in Fig. 2, are effective when revolved at a given speed, to raise the machine vertically to a desired height, they will, when rotated at the same speed, be effective to maintain the machine at substantially the same height, when their lifting power is suitably modified by manipulation of the cranks 40 and consequent change in the relative position of gears 37 and cranks 32. Of course, it will be understood that the path of the wings shown in Fig. 9 is merely illustrative of one of a number of paths they may be caused to traverse, other than the path of substantially maximum efficiency shown in Fig. 2, the variation from the latter path being determined by the positioning of gears 37 with respect to shafts 6, 6', as controlled by the position of cranks 40.

It will be understood that during the period in which the machine is rising from the ground and also when it is desired to maintain it in a substantially constant position after reaching the desired height, the

- mechanism, by means of which the rear edges of the individual wings are raised or lowered as desired, is so manipulated as to cause the nuts 70 to remain substantially at 5 an intermediate position between the ends of their respective screws. In other words, prior to setting the wings in motion to raise the machine, the levers 100 are so positioned by means of their controlling mechanism 10 that all of the clutches 90 and 91 will be thrown out of engagement with their respective gears (it being assumed that the nuts 70 are already positioned substantially midway between the ends of their respective screws) so that when the arms 20 are revolved by their adjacent wing drive shafts to revolve the wings about the latter, the beveled gears 84 will be free to revolve upon the sleeves 83 so that no axial motion will 20 be communicated to the several shafts 63. When, however, it is desired to cause the machine to move forward in the air, either while it is rising or after it has attained a desired height and the path of the wings 25 as hitherto described has been modified so as to maintain it substantially at that height, the levers 100 are actuated in such manner as to cause one of the beveled gears 84 to be engaged by its respective clutch in 30 such manner that the gear will be held stationary with respect to its sleeve 83. As the arms 20 are continuously revolving and carrying around with them the shafts 63, the holding of the gear in fixed position 35 with respect to the sleeve will immediately cause the adjacent pinions 65 to rotate, thereby driving the shafts 63 and 60, and through the medium of beveled gears 58 and 59 the screw 53, thereby moving the nuts 40 70 along the screws to elevate the rear edges of the respective wings in which position the wings will be effective to drive the machine ahead as well as to simultaneously support it in the air. It will be further 45 understood that the amount of forward driving power exerted by the wings will be proportional to the amount of elevation given to their rear edges, a greater elevation, that is, a greater movement of the 50 nuts 70 along their respective screws in the proper direction to elevate the edges of the wings, resulting in a greater forward driving power.
- Similarly, the machine may be readily 55 checked in its forward course by so manipulating the levers 100 that the rear edges of the wings will be depressed and thus render the wings effective to exert a power in opposition to the forward motion of the 60 machine and thereby bring it again to substantially a position of rest in the air. It will of course be understood that in the principal operation of the machine the means for causing the modification of the 65 paths of the wings from that in which they
- exert their maximum power as shown in Fig. 2 to another path in which such power is modified, and the means for elevating or depressing the rear edges of the wings to induce or check a forward movement of the machine in the air, must to a greater or less extent be operated in conjunction with each other depending largely upon the conditions encountered, as for example if the rear edges of the wings are elevated and a portion of the power exerted by each wing thereby directed to cause the forward motion of the machine, the lifting power of each wing will be correspondingly modified and consequently the wings will be set in their path of revolution to exert a greater lifting moment than they were effective to exert prior to the elevation of the rear edges of the respective wings.
- The direction of the flight of the machine 85 may be continuously controlled by suitable operation of the rudder by means of the hand wheels 140 and 148, or the other controlling mechanism supplied, it being possible to both move the forward end of the 90 rudder horizontally to similarly direct the course of the machine and also to move the rear end of the rudder vertically simultaneously if desired, thus turning the machine to the right and left and also directing it up or down at the same time, or at different times conformable to the will of the operator.
- Furthermore, while I have illustrated a machine embodying two pairs of oppositely 100 disposed wing units, I do not thereby desire or intend to limit myself solely to the machine so constructed, as any desired number of pairs of wing units may be employed, and while I have herein described and illustrated one embodiment of my invention with considerable particularity, I do not thereby desire or intend to limit myself specifically to that form of invention, as various modifications and changes may be 110 made therein as desired without departing from the spirit and scope of the invention as defined in the appended claims.
- Having thus described my invention, what I desire to claim and protect by Letters Patent of the United States is:
1. In a flying machine, the combination with a main framework, a plurality of sets of rotatable wing supporting units carried by said frame, concave wings located on said supporting units and manually controlled automatically operating means to feather said wings during the non-working portion of their path of revolution without reversing the position of the individual 120 wings with respect to their respective axes of rotation, the concave sides of the wings facing downwardly during the working portion of their path of revolution.
  2. In a flying machine, the combination 130

6
of a main framework for carrying the mechanism, a pair of oppositely rotatable units adapted to carry a plurality of individual concave wings, means to rotate said units in opposite directions and automatically operating means to effect one oscillation of each of the individual wings on axes, parallel to that of the units during one complete revolution of said units from a horizontal position 10 on their downward working movement to a vertical position on their upward non-working movement and back to a horizontal position at the end of their cycle.

3. In a flying machine, the combination 15 of a main supporting frame, a pair of oppositely inclined supporting struts on said frame, a pair of oppositely rotatable wing carrying units on said inclined supports, a plurality of wings carried by said units having a concave surface on one of their faces 20 adapted to be moved against the air during the downward working movement of said wings and manually controlled and automatically operated means to automatically 25 feather the wings during the vertical non-working upward movement of the same.

4. In a flying machine, the combination 30 of a plurality of oppositely disposed frames, rotatable wing carrying units carried by said frames, means for rotating the same, a plurality of wings carried by said units, means operatively associated with the rotating means to automatically feather said wings during a substantial portion of the 35 vertical movement of said wings upwardly and move said wings to a horizontal position during a portion of the downward working movement of the same without reversing the individual wings with respect to their respective axes of rotation and manually controlled means to simultaneously change the action of the automatic feathering means for each of the sets of wings on the rotatable wing carrying units.

45 5. In a flying machine, the combination of a frame for supporting the mechanism, a plurality of oppositely disposed rotatable wing supports, a plurality of wings carried by said supports, means to rotate said supports, automatic means for feathering the wings during their path of revolution and manually controlled means for maintaining the axis of the individual wings parallel to or inclined to the axis of revolution of said 50 wings to thereby control the flight of the machine in an upward or forward direction.

6. In a flying machine, the combination 60 of a lifting, sustaining and propelling mechanism comprising a plurality of oppositely disposed rotatable units, wings carried by said units and adapted to rotate therewith, the opposed sets of wings moving in opposite directions, automatically operating mechanism for feathering the individual 65 wings during a portion of their path of rev-

olution, means for manually simultaneously adjusting the wings about their respective axes to effect the operation of said automatic feathering means and for effecting an inclination of the individual wings to propel 70 the machine substantially horizontally while being lifted or sustained in air.

7. In a flying machine, the combination 75 of a lifting, sustaining and propelling mechanism comprising a plurality of oppositely disposed rotatable wing carrying units, wings carried by said units, means to rotate said units, automatically operating means for feathering the wings during their path of revolution and means to simultaneously 80 control the position of the individual wings on the oppositely disposed carrying means so that the axis of the wings may be maintained either parallel to or inclined to the axis about which the wings bodily revolve. 85

8. In a flying machine, the combination 90 of a frame for supporting the mechanism, a plurality of oppositely disposed rotatable wing supports, positioned on opposite portions of said frame, wings located on said supports, means carried by the main frame to rotate said supports in opposite directions, manually controlled means actuated by said support rotating means for inclining the axis of the individual wings at an angle 95 to the axis around which said wings bodily revolve.

9. In a flying machine, the combination 100 of a main supporting frame, a set of oppositely rotatable wing carrying units on said frame, a plurality of wings carried on said units, means to rotate said units and means to change the angle of inclination of said wings relative to the axis of rotation of said units, including a gear carried by said 105 units, means operated by said gear to bodily move the axis of said wings, and a plurality of gears engaging said first-mentioned gear on opposite sides thereof adapted to be selectively held from rotation to cause said 110 first-mentioned gear to rotate in either direction as it revolves with its units to thereby bodily move the axis of said wings at an inclination to the axis around which the same revolve. 115

10. In a flying machine, the combination 120 of a main supporting frame, a plurality of oppositely disposed wing supporting units on said frame, a plurality of wings carried by said units, means to rotate said units and revolve said wings, manually controlled means actuated by said rotating units for changing the angle of inclination of the axis of said wings relative to the axis around which said wings revolve, comprising means 125 carried by the units adapted to incline the axis of said wings, a beveled gear on said units for operating said means, a sleeve fixed to said main frame, a plurality of gears located on said sleeve and adapted to engage 130

said first-mentioned gear to rotate the same in opposite directions and manually controlled clutch mechanisms on said sleeve and adapted to engage either of said gears to prevent their rotation as the first-mentioned gear revolves with said units.

11. In a flying machine, the combination of a main frame, a plurality of sets of rotatable wing carrying units on said frame, 10 wings pivoted on said units, means to revolve said units including a rotated gear and automatically operating means to feather the wings during a portion of their path of travel including a relatively stationary gear, a crank arm movable with said units and connected by a link to said wings and operated by a chain of gears from said relatively stationary gear whereby the successive positions of said crank arm are maintained parallel as the wings revolve during the operation of the mechanism.

12. In a flying machine, a plurality of rotatable wing supports, wings carried by said supports, means to rotate said supports and means to automatically feather the position of said wings during a portion of their path of revolution comprising an arm carried by said wings, a link pivoted to said arm and connected to a crank, a gear on said 30 support for controlling said crank, and a relatively stationary gear, said first-mentioned gear being controlled thereby and the gear ratios being so proportioned that, as the support revolves, said first-mentioned 35 gear and crank are maintained in substantially fixed relation to the axis of the support, thus changing, by the connection between the crank and the wings, the position of said wings as the same revolve.

13. In a flying machine, the combination 40 of a main supporting frame, a plurality of rotatable wing supports, wings pivoted on said supports, means to rock said wings as they revolve with said supports comprising a relatively stationary gear and a gear carried by said support, a crank carried by said last-mentioned gear and connected by a link mechanism to said wings whereby when said support with the gear and crank carried thereby revolve, the engagement of the moving gear with the stationary gear causes the said gear to rotate and maintain the crank in parallel successive positions to rock the wings and manually operated means to rotate said relatively stationary gear and 50 hence the gear located on said support to change the position of said crank and thereby change the point in the cycle of revolution of said wings at which the same are rocked on their pivots as they revolve. 55

14. In a flying machine, the combination of a lifting, sustaining and propelling mechanism comprising a plurality of oppositely disposed rotatable units, wings carried by said units and adapted to rotate therewith, 60 the opposed sets of wings moving in opposite directions, automatically operating mechanism for feathering the individual wings during a portion of their path of revolution and means for adjusting said wings 70 on their respective axes for effecting an inclination of the individual wings to propel the machine horizontally while being lifted or sustained in air by said wings.

In witness whereof I have hereunto set my 75 hand this 24th day of August, 1917.

GEORGE H. LOCUSON.
